J. T. JENSEN

WIRE STRETCHER

Filed April 25, 1927

UNITED STATES PATENT OFFICE.

JENS T. JENSEN, OF WESTBROOK, MAINE.

WIRE STRETCHER.

Application filed April 25, 1927. Serial No. 186,213.

This invention relates to a wire fence tightening device.

One of the objects of my invention is to provide a tool which may be applied so that any slackness or looseness may be taken up.

One of the objections and difficulties experienced with wire fences, particularly where there are long runs of the wire between posts, and where the wire has become stretched on account of having been subjected to unusual force by a person climbing over the fence or otherwise, is that unless a means is provided for taking up the slack or compensating for the stretched condition, the wire fence as a protecting means becomes greatly impaired.

A further object is to provide a wire fence tightening tool adapted to be applied to any portion of the wire intermediate the posts and to effectively take up any slack or looseness in the wire by turning the tool.

A further object is to provide a wire tightening device that may be applied to a plurality of wires so that one or more wires may simultaneously be tightened.

A further object is to provide a wire tightening device having an adjustable handle which may be movable laterally of the main body of the tool, or which may be rotated while laterally disposed, a catch or securing member being provided on the handle, the catch being so arranged as to cooperate with the wire after it has been tightened sufficiently to retain the wire tightening tool in position.

A further object is to provide in a wire tightening device, a construction employing a catch whereby the fastener or catch may be adjustably supported so that a catch may be either temporarily or permanently fixed to the wire at different distances from the main body of the tool.

A further object is to provide in a wire tightening tool, a means for securely fastening the wire to the tool before starting to tighten the wire.

For purposes of illustration, one preferred form and certain modifications of the invention are shown in the accompanying drawings and described in the following specification.

In the drawings:

Fig. 1 is an elevation showing the wire tightening tool.

Fig. 2 is a side elevation of Fig. 1, showing the clamp for securing the wire to the tool.

Fig. 3 is a perspective showing the wire tightening device in use, and also shows, by the dotted line position of the handle, how the handle is adjustable laterally of the tool body so that the catch may be fixed to the wire at variable distances from the body of the tool.

Fig. 4 is another perspective view showing the tool in use.

Fig. 5 is a diagrammatic view showing the wire tightening tool applied to a wire fence and tightening a plurality of the strands of the wire extending between fence posts.

Fig. 6 shows a modified form of means for initially securing the wire to the tool before tightening the latter.

The wire tightening tool, as shown, includes a main body portion or post 1 shown as a metallic tube, but it is understood that other suitable material and forms may be used. In order to secure a wire 2 or other member to be stretched to the body 1 of the tool, various means may be employed, but preferably a U-shaped fastener 3 is provided having one leg 4 longer than the other. The longer leg extends through the post so that the end thereof projects on the opposite side. In order to position the wire under the wire fastener 3, the wire retaining member of fastener 3 is withdrawn to a position indicated by the dotted line position in Fig. 2 until the shorter leg of the fastener 3 is clear of the body 1 after which the wire 2 is slipped over the fastener and the fastener is driven into the post. If desired, the projecting end of the longer leg 4 may be riveted over in order to permanently hold the wire in position. If desired to take up the slack in a second wire by the same tool, an angularly disposed slot 5 may be formed in the body 1 of the tool and the second wire may be slipped into the slot 5.

As shown in Figs. 1 and 2, the angularly disposed slot extends downwardly and inwardly from the periphery of the post and is adapted to receive a wire below the U-shaped wire retaining member above referred to. Of course, it is understood that a plurality of slots may be provided for a corresponding greater number of wires and the slots

may be arranged in various relations to obtain any spreading action of the wires as well as a tightening action.

In order to rotate the body of the tool after the wires have been positioned therein, a means is provided for conveniently turning the tool and also for retaining the tool in position after the slack has been taken up and the wire has been stretched the desired amount.

As shown, a handle 6 is provided at one end of the post 1 and is adapted to be adjustable transversely of the body so that a varying leverage may be obtained in tightening the wire. At one end of the handle, there is provided a hook or catch 7. One end of the catch 7 is secured to the handle 6, the other end 8 being bent in the form of a hook and is adapted to slip over the wire after the wire has been properly stretched, thus holding the wire tightening tool in proper position to prevent unwinding of the tool and the release of the tension created in the wire. Figs. 3 and 4 clearly show the relative position of the securing hook 7 on the wire 2 in order to retain the tool in proper position. If desired, the hook portion 8 of the fastener may be closed so as to prevent the accidental release of the wire. The dotted line position of the handle and hook in Fig. 3 indicates the manner in which the hook may be moved to different distances from the post 1 of the tool. If the wire tightening tool is applied to the wire adjacent to the fence post, this adjustable feature may be of advantage. Fig. 6 shows a modified form of means for initially securing the wire 2 to the tool. As shown, pin 9 is passed through the post 1 so that the ends

of the pin extend beyond the body of the post and the wire is initially looped about the pin before tightening the wire.

While one preferred form and certain modifications of the invention have herein been shown, various modifications and changes may be made without departing from the spirit and scope of this invention.

What I therefore claim and desire to secure by Letters Patent is:

1. A wire tightening tool, comprising a body post, means for initially securing a wire to the post, said means including a U-shaped fastener having one leg longer than the other, said longer leg adapted to project beyond the opposite side of the post, a handle at one end of the post and adjustable transversely thereof, and a fastening means at one end of the handle adapted to cooperate with a wire to hold the tool in proper position after the wire has been stretched the desired amount.

2. A wire tightening tool, adapted to stretch a plurality of wires, comprising a body post, means for permanently securing a wire to the body post, said means including a U-shaped member, a second means for receiving a second wire in the body post, said second means including a slot angularly disposed, a handle at one end of the post extending transversely thereof, said handle being rotatably supported in said post, and a fastening means at one end of the handle, adapted to cooperate with the wire after the tool has been rotated to stretch the wires the desired amount.

In testimony whereof I affix my signature.

JENS T. JENSEN.
